UNITED STATES PATENT OFFICE

JACOB TELLER, OF CHICAGO, AND ARTHUR P. SCHULZ, OF BERWYN, ILLINOIS, AS-SIGNORS TO TELLER CORPORATION, OF CHATTANOOGA, TENNESSEE, A CORPORATION OF TENNESSEE

DESIGN FOR A GAS OR ELECTRIC RANGE TOP

Application filed April 6, 1931. Serial No. 39,387. Term of patent 7 years.

To all whom it may concern:

Be it known that we, JACOB TELLER and ARTHUR P. SCHULZ, citizens of the United States, residing respectively at Chicago and Berwyn, in the county of Cook and State of Illinois, have invented a new, original, and ornamental Design for a Gas or Electric Range Top, of which the following is a specification, reference being had to the accompanying drawing, forming a part thereof.

The figure is a front perspective view of the range top showing our new design.

We claim:

The ornamental design for a gas or electric range top, as shown.

JACOB TELLER.
ARTHUR P. SCHULZ.
